UNITED STATES PATENT OFFICE.

WILLIAM JOSEPH STILL, OF LONDON, ENGLAND.

INTERNAL-COMBUSTION ENGINE.

1,306,979

Specification of Letters Patent. Patented June 17, 1919.

Application filed July 17, 1914. Serial No. 851,584.

To all whom it may concern:

Be it known that I, WILLIAM JOSEPH STILL, a subject of the King of Great Britain, and a resident of London, England, 5 have invented certain new and useful Improvements in Internal-Combustion Engines, of which the following is a specification.

This invention relates to improvements in or relating to internal combustion engines and has reference to engines of those types (generally known as Diesel engines) in which the combustible charge is injected into air which has been previously compressed and the temperature of which has 15 been raised to a point at which ignition will take place.

In Diesel engines as at present constructed the air charge must be compressed to a very high degree in order that a satisfactory 20 ignition temperature may be attained, especially at starting with a cool engine.

In engines constructed in accordance with my prior British Letters Patent No. 25356 of 1910 where steam is used expansively at 25 the backs of the pistons, it has been found that the Diesel cycle can be employed with much lower compression pressures after the engine has been started up and run for a short time under steam than is ordinarily 30 necessary and the object of my present invention is to provide ordinary Diesel engines—which have no steam side—with means whereby the cylinders can be pre-heated to and maintained at a temperature 35 such that the compression pressures can be materially reduced. With this object in view my invention consists, broadly, in providing the cylinder jackets with water at or about the temperature at which evaporation takes 40 place at the boiler pressure employed whereby the cylinders are preheated and subsequently, when the engine is running and firing, utilizing the heat of combustion for evaporating water in the jackets whereby 45 the water then operates as a cooling agent to maintain the cylinder wall temperature at or about that to which it was initially preheated. In other words, the pre-heating of the cylinders is attained by providing 50 the cylinder with jackets which form part of a separately fired steam generation system—providing means for setting up a circulation of hot water from the boiler through these jackets, this water being thus 55 maintained at or about the temperature at which evaporation takes place in the boiler.

By this means the hot water which initially heats the interior surfaces of the cylinder raises the temperature of the air contained within such surfaces during the early part 60 of the compression stroke, and therefore reduces the heat lost to the walls as compared with that lost in other forms of internal combustion engines.

In the accompanying drawing which is 65 merely a diagram, the internal combustion engine cylinder is designated by the numeral 1 and this cylinder is provided with a jacket 2 which is associated with a boiler 3 by means of the pipes 4. The boiler is initially 70 fired by a burner or other firing means 5 and subsequently by the burner 6 to which are fed, the exhaust gases from the engine. The steam produced may be led off by a pipe 7 for use as required. 75

When the engine is running and gaining temperature by the combustion of the charge, the water reverses its function and operates, by evaporation, as a cooling agent, thus maintaining the cylinders at a safe temperature, and the steam produced can be utilized either at the backs of the pistons in the manner indicated in my prior specification above alluded to, or in connection with a separate cylinder or steam turbine. The 80 means for firing the boiler may consist of an oil burner which can, if desirable, be put out when the engine is running and there is sufficient waste heat from the cylinders and exhaust gases to generate a useful quantity 85 of steam and maintain the cylinders at the required higher working temperature. 90

It will, of course, be appreciated that engines constructed and operated in accordance with the foregoing conditions will not 95 be subject to the starting up difficulties from which Diesel engines notoriously suffer, but at the same time I wish it to be understood that my invention is not concerned so much with obviating starting difficulties but is 100 primarily a means for enabling the compression pressures necessary to be so reduced that a lighter cylinder structure can be safely employed.

What I claim and desire to secure by Letters Patent is:

A method of working Diesel engines consisting in initially raising the temperature of the water in the cylinder jackets to the temperature of evaporation of an adjacent 110 boiler with which said jackets are in continuous circulation by extraneous heat

whereby the compression pressure at which spontaneous combustion occurs within the engine cylinders is considerably reduced, and subsequently utilizing the heat of combustion for maintaining the boiler at evaporating temperature.

In testimony whereof I affix my signature in presence of two witnesses.

WILLIAM JOSEPH STILL.
